Attorney

UNITED STATES PATENT OFFICE.

CESARE SONCINI, OF BRESCIA, ITALY, ASSIGNOR TO SOCIETÀ ITALIANA ERNESTO BREDA, OF MILAN, ITALY, A JOINT-STOCK COMPANY.

REMOVABLE-BARREL MOUNTING FOR AUTOMATIC FIREARMS.

Application filed June 17, 1926, Serial No. 116,659, and in Italy June 20, 1925.

The present invention relates to means for fixing the barrels in automatic fire-arms of any type; such means allowing the barrel to be rapidly removed and changed without the use of any tool. The invention is characterized by the employment of a tubular connecting sleeve having a large, longitudinal top opening, a specially-formed front opening which permits the barrel to be inclined therein on being taken out or set in, and a specially-formed rear opening provided with a transverse slot in which is mounted a locking sector for retaining the barrel, once the latter has been introduced into the aforesaid rear opening.

The accompanying drawing shows one embodiment of the invention, in which:

Figure 1 is a part-sectional, fragmental view of a fire-arm equipped with the invention, and with the barrel in place;

Fig. 2 is a similar view, but showing the barrel in inclined position prior to being taken off or set in;

Fig. 3 is a cross-section on line 3—3 of Fig. 1; and

Fig. 4 is a view similar to Fig. 3, but with the locking sector lowered and the barrel taken out.

Referring more particularly to the drawing, 1 indicates the sleeve for connecting the barrel 5 to the end 2 of the weapon, which sleeve has its rear end 1' fitted over the reduced portion 2' of said weapon end; the parts 1' and 2' being formed with registering semi-circular slots 3 and 3' designed to receive a locking sector or catch 6 that is pivotally mounted at one end in slot 3, as indicated at 6'.

The rear end 5' of the barrel is likewise reduced to enable it to pass through the interfitting parts 1' and 2 and to project into the bore of a block 9 secured to or integral with the frame of the gun; the wall of said bore having formed in it an annular groove

7 and a pair of oppositely-located longitudinal grooves 7' (Fig. 2), only one of the latter grooves appearing, however. Portion 5' of the barrel is provided adjacent its free end with a pair of diametric lugs 8, 8'; and in front of and substantially in line with the lower lug 8, it is further provided with a depending projection or finger 4. The rear lugs 8 and 8' are designed to be slid rearwardly through the grooves 7' which, of course, lead from the front end of block 9

to the annular groove 7, so that when said lugs reach groove 7 the barrel can be rotated by means of its handle 10, thus bringing them into the position illustrated in Fig. 1, in which the barrel is locked against endwise movement.

The catch or sector 6 mentioned above is utilized, in conjunction with the projection 4 on the barrel part 5', to lock the barrel against rotation after said part has been locked to block 9, as just explained. It will be observed from Fig. 3 that the size of the catch is such that it can occupy not only the outer slot 3 but also the inner slot 3' (or to be more precise, a portion of slot 3'), and that it has a notch or seat 12 (Fig. 4) formed in its inner edge to receive the finger 4, thus preventing the barrel from turning. The catch itself is held in place by means of a rotatable locking screw or detent 13 which it carries at its free end, and the pointed end of which engages in a seat 14 (Fig. 4) in the end portion 1' of sleeve 1.

To take down the barrel, it is merely necessary to release detent 13 from its seat 14 and then move catch 6 out of slots 3, 3' into the position represented in Fig. 4. This unlocks the barrel and enables it to be rotated so as to bring lugs 8, 8' into line with grooves 7', whereafter the barrel can be drawn forward until its reduced rear portion 5' is clear of the interfitting tubular parts 1', 2'. The barrel can then be raised or tilted into Fig. 2 position, due to the special construction of its front end 11 which, as shown, has the wall 11' of its opening tapered or inclined upwardly and rearwardly; and, on assuming this position, can be moved backward through said opening and thus withdrawn from the connecting sleeve.

The barrel can be put back, or a new barrel put in, by carrying out the above operations in inverse sequence.

Modifications and changes in the form and dimensions of the various parts can obviously be made within the scope of the invention.

Having now described my invention, what I claim as new and desire to secure by Letters Patent is:

1. A device for fixing the barrel in automatic fire-arms in such a way as to allow a quick and easy removal or replacement of said barrel, characterized by a connecting sleeve having a large longitudinal top open-

ing, a front opening shaped to permit the barrel to be inclined out of said opening, and a tubular rear portion having a slot in which is mounted a locking-sector hinged to the sleeve and capable of holding the barrel so as to prevent its rotation which would disengage it from the frame.

2. In a removable barrel mounting for automatic fire-arms, the combination, with 10 a barrel having a reduced rear portion provided with a depending projection; of a sleeve for connecting the barrel to the fire-arm and wherein the barrel fits, said sleeve having a tubular rear portion which is 15 adapted to receive the corresponding portion of the barrel and which is provided with a slot; and a catch pivotally mounted in said slot and having a seat to receive said projection and thereby lock the barrel 20 against rotation in the sleeve.

3. In a removable barrel mounting for automatic fire-arms, the combination, with a barrel having a reduced rear portion provided with a depending projection; of a 25 sleeve for connecting the barrel to the fire-arm and wherein the barrel fits, said sleeve having a tubular rear portion which is adapted to receive the corresponding portion of the barrel and which is provided with a 30 slot; and a locking sector pivotally mounted at one end in said slot and provided at its other end with a detent adapted to engage a seat in said sleeve portion so as to lock the sector in place, said sector having a central seat in its inner edge to receive said 35 projection and thereby lock the barrel against rotation in the sleeve.

4. In a removable barrel mounting for automatic fire-arms, the combination, with a 40 barrel having a reduced rear portion provided with a depending projection; of a sleeve for connecting the barrel to the fire-arm and wherein the barrel fits, said sleeve having a tubular rear portion which is 45 adapted to receive the corresponding portion of the barrel and which is provided with a slot; a catch pivotally mounted in said slot and having a seat to receive said projection and thereby lock the barrel 50 against rotation in the sleeve; and means, independent of said catch, for locking the

barrel against endwise movement in said sleeve.

5. In a removable barrel mounting for automatic fire-arms, the combination, with 55 a barrel; of a sleeve for connecting the barrel to the fire-arm and wherein the barrel fits, said sleeve having a large longitudinal top opening and a front opening shaped to permit the barrel to be tilted upwardly into 60 inclined position therein and then removed through the top opening; and means carried by the sleeve at its rear end for engagement with the rear portion of the barrel to lock the latter in place.

6. In a removable barrel mounting for automatic fire-arms, the combination, with a barrel; of a sleeve for connecting the barrel to the fire-arm and wherein the barrel fits, said sleeve having a large longitudinal top opening and a front opening shaped to permit the barrel to be tilted upwardly into 65 inclined position therein and then removed through the top opening; and means engageable with the rear portion of the barrel to hold the latter against endwise movement into tilting position.

7. In a removable barrel mounting for automatic fire-arms, the combination, with 70 a barrel; of a sleeve for connecting the barrel to the fire-arm and wherein the barrel fits, said sleeve having a large longitudinal top opening and a front opening shaped to permit the barrel to be tilted upwardly into 75 inclined position therein and then removed through the top opening; and means engageable with the rear portion of the barrel to hold the latter against endwise movement into tilting position.

8. In a removable barrel mounting for 80 automatic fire-arms, the combination, with a barrel; of a sleeve for connecting the barrel to the fire-arm and wherein the barrel fits, said sleeve having a large longitudinal top opening and a front opening shaped to permit the barrel to be tilted upwardly into 85 inclined position therein and then removed through the top opening; and separate means engageable with the rear portion of the barrel to lock the latter against endwise and rotary movement in the sleeve.

9. In a removable barrel mounting for 90 automatic fire-arms, the combination, with a barrel; of a sleeve for connecting the barrel to the fire-arm and wherein the barrel fits, said sleeve having a large longitudinal top opening and a front opening shaped to permit the barrel to be tilted upwardly into 95 inclined position therein and then removed through the top opening; and means for locking the barrel against movement into tilting position.

In testimony whereof I affix my signature.
CESARE SONCINI.
